HANDLES FOR SECATEURS

Edward A. Rogers, London, England, assignor to Wilkinson Sword Limited, London, England, a British company

Filed Mar. 17, 1969, Ser. No. 16,273

Claims priority, application Great Britain Sept. 18, 1968

Term of patent 14 years

Int. Cl. D8—01

U.S. Cl. D8—5

FIG. 1 is a front view of handles for secateurs in the open position, showing my new design;

FIG. 2 is a rear view thereof, and

FIG. 3 is a side view thereof.

The broken lines are for illustrative purposes only.

I claim:

The ornamental design for handles for secateurs, as shown and described.
